UNITED STATES PATENT OFFICE.

JOHN E. GENN, OF CHICAGO, ILLINOIS, ASSIGNOR TO STEWART-WARNER SPEEDOMETER CORPORATION, OF CHICAGO, ILLINOIS, A CORPORATION OF VIRGINIA.

SPARK-PLUG.

1,328,147.

Specification of Letters Patent. Patented Jan. 13, 1920.

Application filed August 15, 1918. Serial No. 249,939.

To all whom it may concern:

Be it known that I, JOHN E. GENN, a citizen of the United States, and a resident of the city of Chicago, in the county of 5 Cook and the State of Illinois, have invented certain new and useful Improvements in Spark-Plugs, of which the following is a specification, reference being had to the accompanying drawings, forming a part 10 thereof.

This invention is directed to a spark plug for an internal combustion engine having electrodes which are unusually efficient in service, a general assembly particularly economical to manufacture, and including a 15 terminal or binding post adapted to receive a large variety of wire terminals,—these features being hereinafter described and shown in the drawings and particularly set out in 20 the claims.

In the drawings:

Figure 1 is an axial sectional view of a spark plug embodying this invention.

Fig. 2 is a detail section taken as indicated 25 at line 2—2 on Fig. 1.

Fig. 3 is an elevation of the end portion of the plug showing the terminal differently adjusted than in Fig. 1.

Fig. 1 shows the usual outer metallic shell, 30 1, in which the porcelain insulator, 2, is secured by a gland or bushing, 3, screwed into the upper end of the shell, 1. The enlargement, 4, of the porcelain insulator is thus clamped between said bushing, 3, and the internal shoulder, 5, of the shell, 1, with suitable packing washers of copper and asbestos 35 interposed at the points of contact as indicated at 6 and 7. The central electrode, 8, is secured in the end of a conductor member, 9, 40 extending axially through the porcelain, the portion of the bore in the porcelain which accommodates such conductor, 9, being longitudinally corrugated as seen in Fig. 2, and the conductor itself being threaded through 45 a considerable portion of its length from the upper end downward; the diameter of this threaded portion is such that it will be practically centered between the ribs, 10, of the corrugated wall of the bore in the porcelain 50 with just sufficient clearance for rapid assembly, and slight clearance is also provided in the reduced portion of the bore surrounding the electrode, 8. A metallic cap, 11, formed with a threaded hub, 12, engaging 55 the threaded electrode, 9, and with a

flange, 13, whose edge, 14, is crimped or rolled into a groove, 15, formed in the porcelain near its upper end, serves to longitudinally position the conductor, 9, with its lower end abutting the shoulder, 16, in the porcelain, and by thus assembling the parts with a filling of wet cement, 17, occupying all the space between the conductor, 9, and the electrode, 8, and the walls of the porcelain insulator, 2, the cement as it 60 hardens serves to hold the parts securely in position and to render the plug gas tight. It will be noted that while the edges of the threaded portion of the conductor, 9, approach quite close to the ribs, 10, of the corrugated wall, the portions of cement in the intervening grooves, 18, are integrally connected by the cement occupying the grooves of the thread on the conductor, 9, so that the body of cement in the corrugated bore 65 of the porcelain constitutes one continuous mass which is firmly locked against rotation by the corrugation of the bore and which adheres strongly to the conductor, 9, largely by reason of its threads which are 70 particularly well adapted to provide a good bond with the cement if they are formed by pressing or rolling instead of being cut and smoothly finished in the surface of the metal. It may be noted that the corruga- 75 tions formed by the ribs, 10, are discontinued at 19, and from this point to the end of the porcelain the bore is cylindrical to accommodate the hub, 12, of the cap, 11. The grounded electrode, 20, which is fixed 80 in the lower end of the shell, 1, may be a wire of the same material as the electrode, 8, and is bent hook shaped. It is preferably positioned with the point, 21, of the hook adjacent a part of the electrode, 8, which is 85 back from the point, 22, some little distance, so that although when the electrical energy is of relatively low intensity, the spark may be confined to the most closely adjacent parts of the electrodes, 8 and 20, jumping from the 90 point, 21, of the hook to the electrode, 8, it will not be confined to a pair of points when the intensity of the electrical energy becomes sufficient to produce a heavier spark; but, in the latter case, the arc may spread out into 95 a fan shape, the discharge being distributed along the length of the electrode, 20, from its point, 21, back to the bend of its hook form and along the corresponding length of the electrode, 8, out to its tip, 22. With a 100 105 110

constantly heavy discharge, this arrangement will result in a much greater length of life for the electrode than is possible where the discharge is practically forced to occur entirely between the points or ends of the wires.

The projecting portion of the threaded conductor, 9, is fitted with a binding nut, 23, formed with a conical end portion, 24, and 10 with grooves, 25 and 26, for the reception of certain forms of terminal clips, not shown, but commonly applied to conductor wires of the ignition circuit. Certain other forms of terminals such as flat, annular or slotted 15 members, or even the bare ends of the wire itself, may be simply clamped between the metallic cap, 11, of the spark plug, and the flange, 27, of the binding nut when the latter is applied in the position shown in Fig. 20 3. To adapt the plug for connection to a still larger variety of terminals, there is provided a hollow ball, 28, which may be clamped in position as shown in Fig. 1 between the flange, 29, of the binding nut and 25 the top surface of the cap, 11, thus providing a spherical surface which may be engaged by certain terminals designed for the purpose and usually consisting of a pair of substantially parallel spring members having 30 opposed apertures or indentations of somewhat smaller diameter than the ball, 28, and adapted to be seated thereon.

I claim:

1. In a spark plug, an insulating member 35 having a longitudinally corrugated bore, a conductor disposed therein and secured by cement filling the space between the surface of such conductor and the corrugated wall of the insulator.
- 40 2. In a spark plug, an insulating member having a longitudinally corrugated bore, a conductor disposed therein and formed with surface corrugations running transversely of its axis, and cement filling the space between

the corrugated surfaces of the conductor 45 and the insulating bore.

3. In a spark plug, an insulating member having a longitudinally corrugated bore, a conductor disposed therein having a corrugated surface formed by a screw thread 50 thereon, and cement filling the space between the threaded surface of the conductor and the corrugated surface of the insulator bore.

4. In a spark plug, an insulating member, 55 a metallic top for the insulator including a hub portion internally threaded and externally corrugated, the insulator having a bore in which said hub is loosely accommodated, a conductor for the insulated electrode of 60 the spark plug comprising a threaded portion engaged with said hub of the cap and extending into the bore of the insulator, and cement filling the space in the bore around such threaded conductor and said hub of the 65 cap.

5. In a spark plug, in combination with the insulated electrode, a terminal for the same comprising a threaded conductor, a binding nut thereon and an approximately 70 spherical member removably held on said conductor by said binding nut.

6. In a spark plug, an insulator provided with a metallic cap at its outer end, an electrode carried by said insulator and a terminal for the electrode comprising a threaded conductor, a binding nut comprising a flange, and a longitudinally extended portion of smaller diameter, and an approximately spherical shell apertured to receive 80 said smaller portion of said nut, to be held upon the conductor between the flange of said nut and the insulator cap.

In testimony whereof I have hereunto set my hand at Chicago, Illinois, this 12th day 85 of August, 1918.

J. E. GENN.
